UNITED STATES PATENT OFFICE.

DAVID S. HULFISH, OF TORONTO, ONTARIO, CANADA, ASSIGNOR TO CANADIAN INDEPENDENT TELEPHONE COMPANY, LIMITED, OF TORONTO, CANADA, A CORPORATION OF CANADA.

AUTOMATIC TELEPHONE SYSTEM.

1,170,909.

Specification of Letters Patent.

Patented Feb. 8, 1916.

Application filed October 16, 1911, Serial No. 654,872. Renewed June 28, 1915. Serial No. 36,915.

To all whom it may concern:

Be it known that I, DAVID S. HULFISH, a citizen of the United States of America, and a resident of Toronto, county of York, and Province of Ontario, Canada, have invented a new and useful Improvement in Automatic Telephone Systems, of which the following is a specification.

My invention relates to automatic telephone systems in which the telephone lines are grouped into one or more groups, each such group being served by a few switching devices, and in which one of the acts of forming a connection between two lines is the connection automatically of the calling line and a switching device.

My invention comprises means for selecting an idle switching device and means for connecting it to a calling line.

My invention may be used with manual or automatic telephone switching and is dependent of the switching system or type of switches used. I have shown it in the drawings as adapted for the "Lorimer" system of automatic telephone switching.

I illustrate my invention applied to a switch of two movements of selection. I provide means for starting a previously selected switch in one of its movements of selection, and means for stopping it when in that movement it has encountered the subgroup of the calling line; I provide means then operative for starting the switch in its second movement of selection, and means for stopping it when in that movement it has encountered the calling line. I provide means then operative for selecting another switch in readiness to respond to another calling line in the line group.

The circuits and apparatus of my invention are illustrated in the accompanying drawings, two sheets containing four figures, in which—

Figure 1 comprising the central and upper right-hand portion of the first sheet, illustrates the apparatus of the relay and terminal rack, Fig. 2 the upper left-hand portion of the first sheet, illustrates the essential parts of a substation telephone, Fig. 3 across the bottom of the first sheet, illustrates the division starter and all apparatus common to the lines and connective divisions of a group, Fig. 4 comprising all of the second sheet, illustrates the apparatus and circuits of those parts of a connective

division of the "Lorimer" type involved in my invention and also the main battery, common to the entire central office, and 5 shows a modification.

The two sheets register together to form 61 a larger figure for convenience in studying the circuits.

In the figures, numerals smaller than 100 are not reference labels within the ordinary meaning of the term; they are numerals indicating the order or relation of the parts adjacent to which they are found, as indicating the order of contact points in a row, or the order of rows in a contact bank; for example, the numerals 1 to 18 in Fig. 3 are 70 stamped upon the apparatus as built and used and form a part of the apparatus illustrated by the drawing rather than labels referring to it.

Reference numerals 101 to 199 have been 75 reserved for conductors, 200 to 299 for apparatus parts, and 700 to 799 for directory numbers of the telephone lines of the group taken for illustration.

Like numerals refer to like parts throughout the figures.

The group of lines taken for illustration is the eighth group, or group No. 7, containing lines 700 to 799, served by a group of 85 connective divisions of which the first division, served by starter points 1-2-3, is illustrated in Fig. 4, portions of other connective divisions being shown in Fig. 3.

A "Lorimer" switch of the cylinder type, with register, is illustrated in Fig. 4. The 90 horizontal rows of small circles represent the fixed contact points upon the developed inner surface of an annular casting of insulating material; upon these contact points move horizontally from left to right a set 95 of brushes shown in the figure as small flat parallelograms resting upon the points of the 1st, 12th, 23d and 34th vertical sets of points. A controlling magnet or clutch magnet 209 has an armature-dog adapted to 100 engage a notched disk when not attracted, the notched clutch disk being provided with driving means to turn it in the direction indicated by the arrow when the disk is not engaged by the dog, and the armature-dog 105 being adapted to restrain the disk when the two parts are engaged. The disk is attached to the brushes of the cylinder switch. When the clutch magnet is charged by current through its helix, its armature is withdrawn 110

from the disk and the disk is permitted to revolve, carrying with it the brushes of the associated switch. The disk, and therefore the brushes of the switch, may stop only in position corresponding to notches in the periphery of the disk, and these notches therefore represent the only possible stop positions of the brushes of the switch.

In the primary connector of Fig. 4, the stop positions are all in the first quadrant of revolution, as indicated by the location of the eleven notches in the clutch disk. In the pilot clutch, whose magnet is 205 of Fig. 4, there are three stop positions required for the functions of the switch required by my invention; other stop positions may exist as required for the further functions of the switch. In the division starter of Fig. 3, the notches are located to stop the brushes only upon contacts 4, 8, 12 and so on.

In referring to a point in a bank of contacts, mention is made first to the number of its set or vertical row, counting from the left of the figure, and then of its level or horizontal row counting from the top of the bank. Thus, in Fig. 4, plus battery is connected to the point which is found in the 23d vertical set from the left and the 3rd horizontal row from the top; that is, plus battery is connected to point 23X3.

The register is illustrated at the top of Fig. 4. The arcs of small circles represent rows of fixed contact points, upon which move the brushes shown as small rectangles upon the No. 0' set of the points. The brushes are carried by the ratchet, which is under spring tension against its pallet, and is permitted to move step-by-step under control of the register magnet 261. This register complete is carried by the mechanism carrying the cylinder brushes, to which its parts are wired. It is restored to normal position, after having been operated, by mechanical devices which restore it during the second quadrant of revolution of the clutch disk. The cylinder switches of the division starter of Fig. 3 and the pilot switch of Fig. 4 do not have registers associated with them.

The operation of the register of Fig. 4 is as follows: When the magnet 261 is charged, the pallet 206 attached to the magnet's armature has its upper tooth drawn out of engagement with its ratchet 208 and its lower tooth advanced into the path of the ratchet teeth; the spacing of the ratchet teeth and the pallet teeth is such that the ratchet advances through an angle equal to about half the angle between successive teeth; upon the discharge of the magnet 261 the pallet resumes its initial position, withdrawing its lower and advancing its upper tooth, permitting the ratchet 208 to step the remainder of the full tooth distance. When the ratchet 208 is at any half-step position (magnet 261 charged) the brushes 215-216-217 are in-

termediate between contact points and not in electrical connection with any contact point. When the ratchet 208 is at normal or any full-step position (magnet 261 discharged) the brushes rest upon one of the sets of contacts.

In the contact bank of the register of Fig. 4, the first set (the normal set or the No. 0' set) of points has two vacant points, the third point, shown as the bottom point, being connected by wire 125 to the cylinder brush shown in normal position on cylinder point 23X6. The points of the No. 0 set are connected to cylinder brushes on points 1X10, 1X11, 1X12, by wires 126, 127, 129, this set of brushes being the No. 0 set of brushes, and these register points, wires and cylinder brushes being concerned in connections with lines which have the character "0" as the "tens" character of their directory numbers. The next nine sets of register points are analogously connected, each set to its corresponding set of cylinder brushes, the third or "guard" conductor alone being shown in the figure.

Of the twelve points in the bottom level of the register, ten correspond to the ten possible characters of the "tens" place of the directory number of a calling telephone line; these ten are connected to brushes in the cylinder which, when the cylinder is in normal position, as shown in the figure, rest upon cylinder points 1X12, 1X9, 1X6, 12X12, 12X9, 23X12, 23X9, 34X12, 34X9, 34X6 respectively, which are connected to wires 0, 1, 2, 3, 4, 5, 6, 7, 8, 9, respectively, in the cable 144. The cable 144 is the decimal cable and extends from the relay rack of Fig. 1 to homologous points upon all primary connectors serving the 100 lines, a separate decimal cable for each 100 lines, and ten lines served by each wire of the cable.

In Fig. 4, 211 is the units searching relay; 212 is the searching guard relay; 269 is a portion of the bank of contacts of the pilot switch, with bridging brushes shown in the No. 2 position. The clutch magnet is 205, and its clutch disk is cut to stop the brushes on the No. 1 set of points, the No. 2 set of points (as shown) or the No. 3 set of points.

The first point in the bottom level of the register, the point upon which the register brush normally rests (as shown) is connected through wire 125, cylinder point 23X6, wire 158, pilot points 2X1 and 2, (when the pilot brushes are on the No. 2 set of points), to wire 159, which wire 159 passes to the relay rack of Fig. 1 and terminates at the 100 front contact points of the 100 right-hand armatures of the 100 line relays serving the 100 lines of the group served by the primary connector.

In Fig. 1, the 100 lines have each two relays, as shown for line 718, the upper relay

218 being the line or signaling relay for calling, and the lower relay 219 being the cut-off relay for disabling the line relay and for relieving the line conductors of the calling mechanism. With the line idle, both relays are discharged, the helix of relay 219 is from ground or minus battery to the guard wire of the line, and the helix of relay 218 is from plus battery through closed back contacts of relay 219 to both conductors of the line. When the line is grounded, the line relay 218 is charged.

When charged, the left-hand armature of relay 218 of any line connects the first conductor of its line to wire 160 and through helix of relay 224 to earth or minus battery. Relays 224 and 225 are of low resistance, the relay 225 being adjusted to pull up its armature quickly and release it with delay, as will be described in its operation.

When charged, the right-hand armature of the relay 218 of any line removes from the decimal wire of its line the earth connection normally existing through bus wire 183, and connects the register starter wire 159 to earth through wire 183 and the helix of relay 225.

Normally, each wire of the cable 144 is connected through the closed back contacts of ten line relays (as 218) to the helix of relay 225 and to earth; the ten contacts of wires 0 and 1 are shown in Fig. 1, through the contacts of the line relays of lines 700 to 709 and lines 710 to 711, respectively, and the other decimal wires are similarly connected. The ten decimal wires thus normally place the ground of the helix of relay 225 upon the ten directory number points of the decimal register of the primary connector of Fig. 4 and upon the register of every primary connector in normal position, and upon the cylinder points of every primary register. The normal point of the register is normally ungrounded. The action of any calling line is to ground the normal point of the register and to remove the ground from that register point corresponding to the tens digit of the calling line, this action being effected by the movement of the right-hand armature of the charged line relay, as 218.

The primary connector cylinder brushes being in normal position, the register brush 217 cannot remain upon a grounded point.

Ground being placed experimentally upon wire 159, current flows from plus battery on primary cylinder point 23X3, brush in normal position, helix of register magnet 261, brush 217, normal point of register, wire 125, brush in normal position, point 23X6, wire 158, pilot point 2X1, pilot brushes stopped on No. 2 set of points, point 2X2, to wire 159 and to the experimental ground. Magnet 261 is charged, its armature responds, pallet 206 moves, and ratchet

208 as hereinbefore described moves the register brushes to the half-step position, breaking the connection of brush 217 from its normal point.

By advancing to its half-step position, 70 brush 217 has interrupted the current through magnet 261. Magnet 261 is discharged, its armature is released, pallet 206 returns to its normal position, ratchet 208 makes its complementary step, brush 217 75 advances into engagement with its point in the No. 0 set of register points.

By advancing to its No. 0 position, brush 217 has closed a path for current through magnet 261, as follows: From plus battery 80 on primary cylinder point 23X3, brush in normal position, helix of register magnet 261, brush 217, 3d register point of No. 0 set, wire 161, brush in normal position, point 1X12, wire 162, wire 0 of cable 144, 85 (to Fig. 1), through ten closed back contacts and armatures of ten line relays of ten lines. 700-to-709 inclusive, wire 183, helix of relay 225 to minus battery. Relay 225 is charged but effects nothing. Magnet 261 is 90 charged, register brush 217 advances to its half-step position.

By advancing to its half-step position, brush 217 has interrupted the current through magnet 261. Magnet 261 is discharged and brush 217 advances into engagement with its point in the No. 1 set of register points.

By advancing to its No. 1 position, brush 217 closes the path from point 23X3 100 through helix of magnet 261, brush 217, point of No. 1 set, wire 163, point 1X9, wire 164, wire 1 of cable 144, (to Fig. 1), closed contacts of lines 710-to-719, wire 183 and helix of relay 225. Current over this path 105 charges 261, which breaks the charging circuit at 217, which again closes a charging circuit through its No. 3 point, to be broken as before, and so continuously until brush 217 has passed its No. 9 point, when it will 110 come to rest upon its last point, beyond the last decimal wire. With the brush 217 thus advanced beyond the last decimal wire, brush 215 rests upon point 220, and current flows over a path as follows: from plus 115 pole of battery 200, helix of pilot clutch magnet 205, wire 105, pilot point 2X8, pilot brushes stopped on No. 2 set of points, point 2X7, wires 165 and 166, primary 120 point 12X4, cylinder brush in normal position, register brush 215, register point 220, wire 167, cylinder brush in normal position, cylinder point 34X6, wire 168, wire 9 of cable 144, closed contacts of line relays of lines 790-to-799 inclusive, wire 183 helix of 125 relay 225 to minus battery. Pilot clutch magnet 205 is charged and the pilot brushes leave their No. 2 set of points. The pilot switch completes its cycle; in so doing, it 130 revolves the cylinder brushes of the primary

41 connector and thus restores the brushes of the primary connector's decimal register.

To adjust the decimal register to any desired position, the earth connection is removed from the decimal wire of the position in which it is desired that the brushes of the register should stop and ground is applied to the wire 125; the register brush 217 immediately moves into engagement 10 with the open decimal wire and remains there.

The first conductor of the calling line, later serving as a talking conductor, serves preliminarily as a signaling conductor for 15 the identification of the units number of the calling line, as will appear in the description of the operation of the primary connector.

My improved division starter is shown 20 in Fig. 3 with three sets of co-operating pilot points, a fourth set of pilot points being found in points 1X11X12 and 2X11X12 of the pilot bank 269 of Fig. 4. The division starter itself comprises the contact bank 234, 25 of two horizontal rows of points, with one pair of bridged brushes shown on points No. 4, together with the clutch mechanism having the clutch magnet 253, and the relay 252. One omnibus wire 120 extends to 30 point 2X11 on all pilot switches, and a wire 119, individual to each pilot switch extends from pilot point 1X11 to a pair of points in the division starter.

The helix of the starter clutch magnet is 35 connected from plus to minus battery through the back contact of starter relay 252, so that when starter relay 252 is discharged the starter brushes will move continuously. The helix of starter relay is connected from plus battery to bus wire 120, 40 passing to all pilot points 2X11, all pilot points 2X12 being connected to minus battery and pilot brushes being arranged to close 2X11 to 2X12 when the set of pilot 45 brushes are upon their No. 2 set of points; thus starter relay 252 is charged when any pilot switch is upon its No. 2 set of points, and only when some pilot switch is upon its No. 2 set of points are the bridged 50 brushes of the starter at rest.

The operation of the starter in service is as follows: In the conditions of the figures, it is held motionless by the charging of relay 252 over the path through the pilot 55 switch of Fig. 4, whose brushes are at rest upon the No. 2 set of contacts. When the brushes of the pilot of Fig. 4, taken as the first connective division of the group of connective divisions served by the starter of Fig. 3, leave their No. 2 stop position, in the promotion of a telephone call or for any reason, the circuit between pilot points 2X11 and 12 of Fig. 4 is broken, the path through the helix of starter relay 252 is broken, the 60 armature of starter relay 252 is released, and

starter clutch magnet 253 is charged. Starter brushes leave their No. 4 points and engage their No. 5 points. The pilot switch of the second connective division being normal, current flows from plus battery through pilot clutch magnet 205-2, closed pilot points, wire 119-2 and starter points No. 5 to minus battery. Pilot clutch magnet 205-2 is charged and pilot brushes move, reaching their second set of points at about 75 the time that starter brushes reach points No. 6. The pilot brushes stop on their second set of points, closing a path for current from plus battery through helix of starter relay 252, wire 120, closed pilot 80 brushes of division No. 2, to minus battery; relay 252 is charged and magnet 253 is discharged. The pilot brushes continue moving until points No. 8 are reached, when the dog of the armature of magnet 253 85 drops into the notch of the clutch disk and the starter brushes stop.

Had the second connective division been found with its pilot brushes off normal, upon neither the first nor second set of 90 points, the connection temporarily of minus battery through the starter brushes to wire 119-2 would not have resulted in any action in the division; starter relay 252 would not have been charged, and the starter 95 brushes would now move continuously until points No. 9 were engaged, when the clutch magnet 205-3 of the next division, or of the first idle division would have been charged and by current over a path closed 1 by the starter brushes, and the pilot brushes of the idle division would have moved to their No. 2 set of points to charge the starter relay 252 to stop the starter brushes to prevent the starting of further pilot switches 1 until the connective division thus selected and thus set off normal should have been advanced further than its No. 2 set of points by some means other than the starter control.

With reference to the starter, the connective divisions have three conditions, as evidenced and distinguished by the positions of their pilot switch brushes. (a) The pilot switch may be idle, awaiting selection by the starter, in which condition its pilot brushes are upon their No. 1 set of points, and path is closed through from plus battery to the starter points. (b) The pilot switch may be awaiting a call from a telephone line, having been selected by the starter to serve the next call, in which condition its pilot brushes are upon their No. 2 set of points and are holding the starter relay 252 charged, preventing the starter from advancing any other pilot switch to a similar condition. (c) The pilot switch and its division may be promoting, sustaining or disrupting a connection, in which condition its pilot brushes are not

upon either the No. 1 or No. 2 set of points and the starter and division are mutually independent. The starter relay 252 is adapted to sustain continuous current from the battery 200.

The requirement of the system of my invention with reference to the telephone substation equipment is that within that equipment such a change shall be possible as to effect the charging of the line relay, as 218, of the telephone line. The central office ground connection required in the figures upon the first conductor of the calling line, as upon wire 121 of line No. 705, is supplied by the line relay when charged, by connecting the first conductor of the line through the left-hand armature of the line relay to wire 160 and through the helix of low-resistance relay 224 to earth. It is obvious that by connecting the right-hand back contact of relay 219 to minus battery instead of to the helix of 218, the lifting of the receiver at the telephone substation would provide the required condition. See Fig. 5.

The operation of the system of my invention is as follows: A telephone user, to call from the station as that shown in Fig. 2, manually advances the arm 242 into engagement with the point 244. This station is upon line 705. Current flows and charges relay 226 over the following path: plus sign, helix of relay 226, wire 191, wire 121 (to Fig. 2), arm 242, point 244, to earth or minus battery. Relay 226 being charged, current flows and charges relay 224 over the following path: from plus sign, helix of relay 226, armature and front contact (now closed) of relay 226, wire 160, helix of relay 224, to minus sign or minus battery. Relay 226 being charged, current flows also and charges register magnet 261 over the following path: from plus battery on primary cylinder point 23X3, brush in normal position, helix of register magnet 261, brush 217, normal point of register, wire 125, brush in normal position, point 23X6, wire 158, pilot point 2X1, pilot brushes stopped on No. 2 set of points, point 2X2, wire 159, (to Fig. 1), to front contact point of right-hand armature of relay 226, armature (now attracted) of relay 226, through closed back contacts and armatures of uncharged relays of lines, downward to wire 183 and through helix of relay 225 to minus battery. Relay 225 also is charged. The register of Fig. 4 now operates as described and stops on the No. 0 set of points, corresponding to the tens digit of the line No. 705. During this operation, relay 225 has had its armature attracted but now releases it, and current flows to charge primary connector clutch magnet over the following path: from plus sign, helix of clutch magnet 209, wire 110, pilot points 2X3 and 4, wire 184, back contact and armature of relay 225, armature and front contact (now closed) of relay 224, to minus battery.

ture of relay 211, wire 185, (to Fig. 3) back contact and armature of relay 225, armature and front contact (now closed) of relay 224, to minus battery.

By the charging of the clutch magnet 209, the primary connector brushes are driven over the contacts of the cylinder until line 705 is found, when searching relay 211 is charged by current over the following path: from plus sign, helix of relay 211, armature 75 and back contact of relay 212, wire 186, pilot points 2X6 and 5, wire 111, brush six points off normal, on point 18X4, register brush 215, register point of No. 0 set of points, wire 126, brush six points off normal on cylinder point 7X10, wire 121, (to Fig. 1), wire 191, left-hand armature and contact (now closed) of relay 226, wire 160, helix of relay 224, to minus battery.

By the charging of relay 211, the clutch magnet 209 is discharged and the brushes of the primary connector stop on line No. 705. Had line No. 704 been busy, then when the brushes engaged that line, in their progress toward line 705, relay 212 would have been charged by current over the following path: from plus battery upon primary connector cylinder point 6X12, guarding the busy line 704, wire 161, bottom point of register set No. 0, brush on cylinder point 17X6, wire 95 113, pilot points 2X9 and 10, helix of relay 212 to minus battery. Relay 212 being charged, the circuit of the helix of relay 211 is opened, preventing the seizure of the busy line 704 by the searching primary connector.

The plus battery upon primary connector cylinder point 6X12 mentioned in the paragraph above as guarding the busy line 704, exists upon that point because the line 704 while guarded, is connected with some connective division or primary connector other than the testing and operating division above considered and the plus battery upon that point is obtained through this other division from plus battery upon pilot switch point 3X10 over brushes on the No. 3 points to pilot point 3X9, wire 113, brush 217, wire 161 and brush on 12th level adjusted upon point 12X6 to connect with line 704. The 110 circuit, having extended from plus battery thus far through the said other division, passes through the multiple line wire to testing division and thence continues over the circuit traced in the paragraph above. 115

By the charging of relay 211, the clutch magnet 205 of the pilot switch is charged by current over the following path: from plus sign on main battery 200, helix of clutch magnet 205, wire 105, pilot points 2X8 and 125 7, wire 165, front contact and armature (now attracted) of relay 211, wire 185, (to Fig. 2), back contact and armature of relay 225, armature and front contact (now closed) of relay 224, to minus battery. 130

By the charging of the clutch magnet 205, the pilot switch brushes move, stopping in their third stop position, on contact set No. 3. In this position, plus battery is connected through pilot points 3X10 and 9 to wire 113 and to the guard wire of line 705, the cutoff relay of that line being charged by current over the following path; from plus sign, pilot points 3X10 and 9, wire 113, primary connector cylinder point 18X6, cylinder brush six points off normal, brush 217, wire 161, wire 123, (to Fig. 1), wire 193, helix of cut-off relay 227 to minus battery. The charging of the relay 227 discharges relay 226. The discharge of relay 226 discharges relay 224.

The departure of the pilot brushes from the No. 2 set of points discharges relay 252 of Fig. 3 and the division starter operates to select an idle pilot switch, which it advances to the second set of points in readiness to serve the next call.

The subsequent operations of the connection in response to the call thus received and assigned to a connective division may be in accordance with the general practice in exchanges of the "Lorimer" type of apparatus.

What I claim is:

- 30 1. In an automatic telephone system, a selecting switch of two movements of selection; two sets of indicator conductors, each set indicating stop positions in one movement of selection; a line having eligible points in said switch; a relay pertaining to said line and controlling circuits of two wires one in each of said sets, said two wires thus controlled determining the position of the said switch for the selection of the said points of said line, a series of circuits for moving said switch in its first movement of selection, and a relay in series with all of said circuits of said series and controlling said switch to move in its second movement of selection.
- 35 2. In an automatic telephone system, a selecting switch of two movements of selection; two sets of indicator conductors each set indicating stop positions in one movement of selection; a plurality of relays each controlling a conductor in each set; a circuit for moving the switch in its first movement and for stopping it in that movement in the stop position indicated by the conductor of a charged one of said relays, and a slow acting relay in said circuit and in series with the switch-driving means of the circuit and acting after said switch-driving means has ceased operating, said slow relay controlling the starting of the said switch in its second direction of movement.
- 40 3. In an automatic telephone system, a selecting switch of two movements of selection; two sets of indicator conductors each set indicating stop positions in one move-

ment of selection; means for changing the electrical status of one conductor of each set; and means for moving the switch in two movements and for stopping it in each movement in the stop position indicated by the changed conductor, a plurality of circuits used successively in propelling said switch in its first movement of selection, a relay in series with all of said circuits acting to start the switch in its second movement of selection only after its first movement of selection has been accomplished.

4. In an automatic telephone system, a selecting switch having two movements of selection; means for indicating within each switch a stop position in each movement of selection; means for accomplishing the first movement to the indicated stop position; means subsequently operable for accomplishing the second movement, said means for accomplishing the second movement comprising in part, a slow acting relay which is included in series with said means for accomplishing the first movement.

5. In an automatic telephone switch, a selecting brush; contact points for said brush; a driving means for said brush; a circuit including the brush and its contacts and when closed, controlling said driving means to move the brush; normally closed paths from said points except the normal point; means for closing the path through the normal point and for opening the path of another point, and a slow relay in series with all of said closed paths, said relay operating to close its controlled circuit only when no current flows through any of said paths.

6. In an automatic telephone switch, a selecting brush; contact points for said brush; a driving means for said brush; a circuit including the brush and its contacts and when closed controlling said driving means to move the brush; normally closed paths from said points except the normal point; a line; points in said switch and pertaining to said line; a relay pertaining to said line, said relay when charged operating to close the path through some normal point and open the path of another point, and a slow relay in series with all of said closed paths and acting to close this circuit only after current has ceased through ~~any~~ and all of said closed paths for a predetermined period.

7. In an automatic telephone switch, a selecting brush; contact points for said brush; a driving means for said brush; a circuit including the brush and its contacts and when closed controlling said driving means to move the brush; normally closed paths from said points except the normal point; a line; points in said switch and pertaining to said line; a relay pertaining to said line, said relay when charged operating to close the path through some normal point and open the path of another point, and a slow relay in series with all of said closed paths and acting to close this circuit only after current has ceased through ~~any~~ and all of said closed paths for a predetermined period.

ating to close the path through some normal point and open the path of another point; said differentiated point indicating the position of said brush required in said switch 5 for the selection of the points pertaining to said line, and a slow relay in series with all of said closed paths and operating to close its controlled circuit only when said brush has attained the position indicated by said 10 differentiated point.

8. In an automatic telephone system, a switch of two movements of selection; an electric circuit controlling the motion of said switch in the first movement of selec-

tion, a relay in series in said circuit and 15 holding its armature attracted during the motion of said switch in the first movement of selection; and a second electric circuit controlling the motion of said switch in the second movement of selection and itself controlled in part by said relay.

Signed by me at Toronto, county of York, and Province of Ontario, Canada, in the presence of two witnesses.

DAVID S. HULFISH.
